UNITED STATES PATENT OFFICE.

WILLIAM P. BROWN, OF ZANESVILLE, OHIO.

WHEELED CULTIVATOR.

SPECIFICATION forming part of Letters Patent No. 356,613, dated January 25, 1887.

Application filed May 9, 1885. Serial No. 164,946. (No model.)

To all whom it may concern:

Be it known that I, WILLIAM P. BROWN, of Zanesville, in the county of Muskingum and State of Ohio, have invented certain Improvements in Wheeled Cultivators, of which 5 the following is a specification.

This invention has reference to what are commonly known as "parallel" or "flexible" wheeled cultivators, which are so constructed 10 as to admit of the two plows or cultivators moving backward and forward independently of each other, each plow being turned parallel to its own horse.

The invention consists in various details of 15 construction, having in view the automatic backward movement of each wheel as the adjacent plow is elevated in order to secure a proper poise or balance of the machine, the attachment of the springs for lifting the plows to 20 the movable axles in such manner that their relation to and action upon the plows will remain unchanged, notwithstanding the motion of the axle, and to means whereby either end of the axle may be secured against a swinging 25 motion independently of the opposite end.

In the accompanying drawings I have represented a machine having my improvements embodied therein in the preferred form; but it is to be distinctly understood that the improvements may be applied in other forms and 30 to other machines in a manner which will be readily understood by the skilled mechanic without departing from the limits of the invention.

35 Referring to the drawings, Figure 1 represents a perspective view of my machine, one of the main wheels being removed to expose other parts to view. Fig. 2 represents in perspective one end of the main axle with the 40 plow connecting or coupling devices and the parts adjacent thereto. Fig. 3 is a side elevation of the parts represented in the preceding figure, the axle, sleeve, and coupling being shown in cross-section. Fig. 4 is a rear 45 face view of the clevis or draft-head.

In the drawings, A represents a rigid horizontal tongue or draft-pole, which may be of any appropriate form and construction; and B, the divided arched axle jointed to the frame 50 and provided at its respective ends with the main or ground wheels C. The axle is com-

posed of two halves, each consisting of an upright portion having the lower end extended horizontally outward to receive the wheel, and the upper end extended horizontally inward into or through the tongue, in which it is loosely seated, so that the lower end may swing forward and backward, this construction permitting each wheel to advance and recede independently of the other and of the 60 tongue or frame. 55

The tongue may be provided, as shown, with fixed side plates to form bearings for the ends of the axle, and the latter may be provided, as shown, with adjustable collars a or 65 equivalent devices, to admit of the axles being adjusted to change and fix the distance between the wheels.

On each of the outer lower ends of the axle, inside of the wheel, I mount a rotary sleeve, 70 D, provided with an upright arm, d, connected by a link, c, to the lower end of an elevating-spring, L, the upper end of which is bolted rigidly to a plate or projection on the upper part of the axle. The spring tends to turn the 75 sleeve forward and lift the plows, as in various patents heretofore granted to me.

An important feature of the present invention lies in the fact that the lifting spring is connected to and moves with the swinging 80 axle, so that the changing position of the axle has no effect whatever upon the tension of the spring, which is permitted to act in the same manner and with the same effect as with a rigid axle. Against the front side of the sleeve 85 D is seated a plate, E, provided with one or more holes to receive a draft-rod, hereinafter referred to, and against the rear side of the sleeve there is seated a plate, F, forming a bearing for the front face of a forked plate or 90 clevis, G. Two horizontal bolts, H, one above and the other below the axle, are extended through the parts E, F, and G, holding them firmly in place with respect to each other and to the sleeve, which latter is provided with a 95 longitudinal spline, e, engaging the plate F, so that the entire coupling device is compelled to rotate with the sleeve, while at the same time the loosening of the bolts will permit them to be adjusted lengthwise of the sleeve at will, 100 in order to vary the distance between the plows. To the forked plate or clevis G is connected

by a vertical eyebolt, J, the forked head or draft device I, to which the plow-beams are rigidly secured.

The plows are free to swing laterally around the pivot J, and are permitted to rise and fall by the rotation of the entire coupling device about the axle, as usual in this class of implements.

The opposing faces of the parts F and G are made of circular form with interlocking teeth or serrations, and the part G is provided with curved slots, through which the bolts pass, as shown in Figs. 3 and 4, this construction permitting the part G to be tipped or turned laterally in a vertical plane, so as to incline the plow-shovels laterally to the right or left, as occasion may require. The plate or elevis G and the draw-head I are each widened laterally and provided with a series of holes to receive the pivot J, this construction permitting the pivotal point to be shifted laterally with respect to the plow and the draft-head, as the nature of the soil or other controlling circumstances may render advisable.

To the upper ends of the respective pivots J, I attach rods M, extended forward and upward, and adapted to be connected at will to opposite ends of the evener N, pivoted centrally to the tongue or to opposite ends of a cross-bar, O, bolted rigidly to the tongue. Owing to this connection it follows that when either plow is lifted the end of the axle to which it is attached and the adjacent wheel thereon are both compelled to move backward, an action which is highly advantageous in that a better balance and poise is secured. The essence of my invention in this regard consists in connecting with the swinging axle and a plow jointed thereto a rod or equivalent controlling device in such manner that the rising motion of the plow will be accompanied by a backward movement of the axle, and it will be manifest to the skilled mechanic that the details may be variously modified to this end.

Owing to the fact that the rods M are attached above the horizontal axes of the plow-couplings, the forward strain of the rods tends to lift the beams and shovels. This lifting motion is resisted to a greater or less extent by the draft-rods, and as the result of these two opposing forces, which vary in relation to each other, the shovels are given a slight rising-and-falling motion, which causes them to scour in a very efficient manner, so that their surfaces are kept clean and in an operative condition. It will be observed, therefore, that the rods M, connecting the evener to the plows or plow-couplings at points eccentric to the axis of the latter, serve the threefold purpose of holding the axle in position so that the machine cannot fall down, of moving the axles forward and backward as the plows are raised and lowered, and of imparting the "live" action of the shovels in the soil.

I am aware that rods have been extended from an evener directly to the opposite inde-

pendent swinging ends of an axle, and to such construction I lay no claim.

To the ends of the evener or equalizer N are jointed depending arms O', designed to receive the whiffletrees or other draft devices, and connected at their lower ends by rods P to the plates E of the coupling. When the rods M are attached to the evener, I secure all the advantages arising from the use of the ordinary evening or equalizing devices in this class of machines, the draft of the frame being distributed between the two animals, while at the same time each animal is compelled to draw its own plow and each plow permitted to move freely forward and backward independently of the other. When, however, the rods M are attached to the fixed bar, the machine becomes rigid or inflexible so far as the team is concerned, the backward movement of the wheels as the plows are raised occurring in the same manner as when the rods are attached to the evener.

Having thus described my invention, what I claim is—

1. In a wheeled cultivator, the combination of a main frame, a swinging axle, plows jointed to said axle to swing vertically, and rods or connections extending from the frame to the plows or plow-couplings at points eccentric to the axis around which the plows swing in rising, whereby the elevation of either plow is caused to produce a backward movement of the axle, and vice versa, thereby maintaining the proper poise or balance of the machine upon its wheels.

2. In combination with the tongue, the divided arched axle jointed thereto, the sustaining-wheels, the plows coupled to the axle, the cross-bar or evener, and the rods extended from the plow-couplings to opposite ends of the evener, whereby the rising motion of either plow compels a rearward motion of its axle-section and wheel.

3. The tongue provided with the bar O or similar rigid connection, and with the pivoted evener N, in combination with the divided arched axle having its parts jointed to the tongue, the plows coupled to the ends of the axle, and the rods M, attached to the plow-couplings and adapted for connection at will to the bar O or the evener, whereby the machine may be rendered flexible or rigid when in action, as occasion may demand.

4. In combination with a tongue or frame, a swinging arched axle jointed thereto, wheels on said axle, plows coupled to the axle, and detachable rods, substantially as described, to prevent the swinging motion of the axle, as circumstances may demand.

5. In combination with a swinging cultivator-axle and a plow coupled thereto, a lifting-spring secured to and movable with the axle, and connected with the plow-couplings, substantially as described, whereby the relation between the spring and plow is maintained as the axle swings to and fro.

6. The tongue or frame, the arched swinging axle jointed thereto, the plow-couplings mounted on the axle and provided with the projecting arms, and the spring-arms bolted 5 to the axle and connected to the coupling-arms.

7. The tongue, the cross-bar or evener thereon, and the jointed swinging axle and its wheels, in combination with the plow-couplings adapted to rotate vertically, the 10 plows united to the couplings by vertical pivots, and the rods extending thence to the respective ends of the evener, whereby the plows are permitted to swing laterally without affecting the position of the axle, but the latter 15 compelled to swing backward and forward as the plows are raised and lowered.

8. In a wheeled plow having an axle the two ends of which are provided with wheels and arranged to swing forward and backward independently, plows coupled to said axle, 20 and means, substantially as described, whereby either end of said axle may be prevented from swinging, leaving the other end free.

In testimony whereof I hereunto set my hand in the presence of two attesting witnesses.

WILLIAM P. BROWN.
